US00D779449S

(12) **United States Design Patent** (10) **Patent No.:** **US D779,449 S**
Kim et al. (45) **Date of Patent:** **** Feb. 21, 2017**

(54) **PORTABLE ELECTRONIC DEVICE**(71) Applicant: **Samsung Electronics Co., Ltd.**, Suwon-si (KR)(72) Inventors: **Namsu Kim**, Seoul (KR); **Dohyung Ha**, Gwangmyeong-si (KR); **Saehee Lee**, Incheon (SK); **Hyunsook Kim**, Seoul (KR)(73) Assignee: **Samsung Electronics Co., Ltd.**, Suwon-si (KR)(**) Term: **14 Years**(21) Appl. No.: **29/504,002**(22) Filed: **Oct. 1, 2014**(51) LOC (10) Cl. **14-03**

CLAIM

The ornamental design for portable electronic device, as shown and described.

DESCRIPTION

FIG. 1 is a front perspective view of a portable electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

1 Claim, 8 Drawing Sheets(56)
